UNITED STATES PATENT OFFICE.

JOHN T. SIMPSON, OF NEWARK, NEW JERSEY.

CONCRETE BUILDING.

1,409,251.

Specification of Letters Patent. Patented Mar. 14, 1922.

Application filed March 6, 1918. Serial No. 220,708.

To all whom it may concern:

Be it known that I, JOHN T. SIMPSON, a citizen of the United States, residing at Newark, county of Essex, and State of New Jersey, have invented a certain new and useful Improvement in Concrete Buildings, of which the following is a specification.

My invention relates to concrete structures, and more particularly to what may be 10 termed a composite structure composed of shop cast reinforced concrete elements, field cast reinforced concrete elements, metal sheathing or lathing, moisture-proof sheeting, and exterior and interior coatings applied on the job.

The objects of my invention are to provide a fire-proof building of great simplicity and cheapness, which will be moisture and frost proof, of which nearly all of the members 20 going to make up the structure will be built in a factory and therefore be made under the best possible conditions and by means of permanent apparatus whereby the elements may be perfect as regards dimensions, 25 density and finish and whereby they may be manufactured at a minimum cost.

These and further objects will more fully appear in the following specification and accompanying drawings considered together 30 or separately.

I have illustrated one embodiment of my invention in the accompanying drawings in which like parts are designated by similar characters of reference and in which—

35 Fig. 1 is a sectional view of a wall of a building constructed according to my invention, the section being taken on the line 1—1 of Fig. 3.

Fig. 2 is a section on the line 2—2 of 40 Fig. 1.

Fig. 3 is a section on the line 3—3 of Fig. 1.

Fig. 4 is a detail horizontal section illustrating the manner of securing shop-cast 45 sills, lintels, struts and braces in position.

Fig. 5 is a detail perspective view of a shop-cast stud.

Fig. 6 is a detail sectional view of the field cast belt or ribbon.

50 Fig. 7 is a front elevation of a house constructed according to my invention, the outer surface being removed.

Fig. 8 is a detail sectional view of a modified form of flooring.

55 Fig. 9 is a detail view of a modification.

Fig. 10 is a detail sectional view illustrating one method of waterproofing.

Fig. 11 is a similar view of a modification.

Fig. 12 is a detail view of another modification.

Fig. 13 is a similar view of a further modification, and

Fig. 14 is a plan view of a partition stud.

In carrying out my invention I provide a building comprising shop cast studs 1, sills 60 2, lintels or headings 3, beams and rafters 4 and struts or braces 5, of reinforced concrete.

The studs for exterior walls and interior partitions are preferably of a length approximately equal to the distance between the floor and ceiling of each story of the building to be erected. Each stud is notched as at 6 for the reception of the end of the sill, 70 lintel or strut as the case may be. The ends of each stud 1 are each provided with a cavity 7 for a purpose to be presently described. In the bottom of each notch 6 is a similar cavity 8 and the ends of each sill, lintel and strut has a similar cavity 9. 75

The reinforcements 10 of each stud project from the end thereof and the reinforcements 11 of the beams and rafters likewise project from the ends of those members.

Opposite faces of the studs 1, lintels 3 85 and struts 5 are provided with wire loops or hairpins 12 anchored therein with the bights projecting therefrom. The floor beams 4 have similar loops 13 projecting from their lower edges. 90

In erecting the building a foundation course 14 is placed in position to define the shapes of the building with its rooms, halls, etc. The course 14 may be either field or shop cast, preferably the former. If field 95 cast its reinforcing members are placed in position within a mold having an offset at its inner upper edge and the concrete is poured into the mold. When the level of the course 14 reaches a certain height the 100 studs 1 are placed where desired with the projecting reinforcements extending into the mold. Before the studs are so placed a dowel 15 is positioned in the cavity 7 at the lower end thereof and the cavity is filled with concrete. The mold is now filled with concrete to its ultimate height embedding the projecting reinforcements and the projecting ends of the dowels. 105

A dowel 16 is seated in the cavities 8 of 110

each stud and the cavities are filled with concrete. The cavities 9 in the ends of the sills, lintels and struts are filled with concrete and before the same hardens and during the 5 positioning of the studs the dowels 16 are forced into the cavities 9 thereby rigidly securing the said members to the studs and retaining the same in their vertical positions.

If desired the horizontal members may be 10 provided with integral dowels 17 to fit in sockets 18 in the studs as shown in Fig. 12 or the dowels 17 may be grouted in place in the notches 6 as shown at 19 in Fig. 13.

A mold is now placed in position at the 15 upper ends of the studs 1 and enclosing the projecting reinforcements 10. A dowel pin 20 is placed in an upright position in the cavity 7 at the top of each stud. Reinforcements 21 are positioned in the mold. The 20 ends of the floor beams or rafters, as the case may be, are placed in position with their ends resting on the studs thus far positioned and with their projecting reinforcements projecting into the mold and preferably en- 25 gaging the reinforcements 21. The inner upper edge of the mold is offset for a purpose to be mentioned.

Liquid concrete is now poured into the mold filling the same, enclosing the ends of 30 the beams, embedding the reinforcements 21 and the projecting reinforcements of the studs and beams, and filling the cavities 7 in the top of the studs and embedding the dowel pins 20. Before the concrete in the 35 mold hardens a dowel pin 22 is forced into the concrete of the field cast member 23 in the mold and directly over each pin 20 and the framing for the next story of the building 40 is erected as before.

The offsets in the molds of the field cast members 14 and 23 permit the formation of a shelf 24. The field cast member 23 will extend around the entire building in the form of a belt or spandrel beam. The shelf 45 24 will support the floors between the beams 4 and at the walls parallel to the beams.

The outer surface of the building is composed of metal lathing or sheathing 25 covered with stucco 26 and the interior walls 50 and partitions are made of similar lathing covered with plaster. The lathing of sheathing may be of any desired form and is spaced away from the shop cast members by means of spacers 27 in order that 55 there will be an air space between the exterior and interior coverings even at the field and shop cast members. The spacers 27 may be integral with the lathing as shown in Fig. 10 or may be separate elements as shown in 60 Fig. 11.

A sheet 28 of moisture proof material is used in conjunction with the lathing or sheathing to prevent moisture from penetrating the walls. If desired a plurality 65 of sheets of such water-proof may be utili-

zed on each side of the framework as shown in Fig. 11.

The floor beams are provided with nailing blocks 29 to which sleepers 30 are secured. Metal lathing 31 is laid on top of 70 the beams beneath the sleepers and a bed 32 of concrete is laid upon the lathing to the level of the top of the sleepers. Wood or other flooring is secured to the sleepers over the concrete bed. 75

Instead of employing the nailing blocks sleepers and flooring metal lathing may be secured to the tops of the beams by means of loops or hairpins 33 and a concrete floor 34 laid thereon as shown in Fig. 8. 80

The ceilings 35 are constructed in the same manner as are the interior walls and secured in place by means of the loops 13.

In structures designed to carry heavy loads I may provide field cast braces or 85 brackets 36 as shown in Fig. 9. The studs 1 and beams 4 may be notched as at 37 to expose one or more of their reinforcements. Supplemental reinforcements 38 may be attached to such exposed portion. A mold in 90 which reinforcing members are laid is placed in position and the member 36 cast therein and embeds the supplemental reinforcements.

At the tops of the partition studs 39 a 95 mold 40 is placed in position and concrete is poured into it to the level of the tops of the beams 4 to embed the projecting reinforcements and to form a foundation for the next superposed stud. 100

In accordance with the provisions of the patent statutes, I have described the principle of my invention, together with the means which I consider to represent the best embodiment thereof, but I desire to 105 have it understood that such means are merely illustrative and the invention may be carried out in other ways.

Having now described my invention what I claim and desire to secure by Letters 110 Patent is as follows:—

1. A building comprising vertical shop cast reinforced concrete elements arranged end to end and spaced apart, and side by side and spaced apart; a field cast reinforced 115 concrete member formed between the floor and ceiling between the ends of said vertical elements to secure the ends to one another and extending from one pair of opposing vertical elements to an adjacent pair of vertical opposing elements, and a projecting load carrying ledge or shelf extending the entire length of the field cast member; and floor beams having their ends embedded in said field cast member. 120

2. A building comprising a series of vertical shop cast reinforced concrete elements spaced apart, there being a conical socket in the end of each element, a pin extending from the bottom diminished end of each 130

- socket, a horizontal field cast reinforced concrete load carrying member engaging the end of each of the vertical elements and flowing into the sockets thereby embedding 5 the pins.
3. A building comprising a series of vertical shop cast reinforced concrete elements spaced apart, there being a conical socket in each end of each element, a pin extending 10 from the bottom diminished end of each socket, a horizontal field cast reinforced concrete load carrying member engaging each end of the vertical elements and flowing into the sockets thereby embedding the pins.
- 15 4. A building comprising a series of vertical shop cast reinforced concrete elements spaced apart, there being notches in each element, said notches being in alignment, a shop cast reinforced concrete element extending 20 horizontally between adjacent vertical elements, the ends of the members resting in aligned notches, there being a socket in each vertical element at the bottom of each notch, there being a similar socket in 25 each end of each horizontal element in alignment with the notch sockets, a pin or dowel engaging adjoining sockets, said sockets being filled with green concrete whereby the said pin is temporarily positioned and upon 30 setting of the concrete in the sockets is rigidly secured within said sockets and forms part of the reinforcing systems of both elements.
5. A building comprising a series of vertical shop cast reinforced concrete elements spaced apart, there being horizontal grooves 35 in each element, shop cast reinforced concrete elements arranged horizontally between the vertical elements and supported
- at their ends in oppositely disposed grooves 40 in adjacent elements, means for securing the horizontal elements in position, and a horizontal field cast reinforced concrete member engaging an extremity of all of the vertical elements, said elements and member 45 having loops projecting therefrom, a metallic lathing or sheathing secured to the loops, and a field made coating of plastic material secured to the lathing or sheathing, said coating forming the entire exposed surface 50 of the walls of the building.
6. A building comprising a series of vertical shop cast reinforced concrete elements spaced apart, there being notches in each element, said notches being in alignment, a 55 shop cast reinforced concrete element extending horizontally between adjacent vertical elements, the ends of the members resting in aligned notches, there being a socket in each vertical element at the bottom of each 60 notch, there being a similar socket in each end of each horizontal element in alignment with the notch sockets, a pin or dowel engaging adjoining sockets, said sockets being filled with green concrete whereby the said 65 pin is temporarily positioned and upon setting of the concrete in the sockets is rigidly secured within said sockets, and forms part of the reinforcing systems of both elements, and a spandrel beam of field cast reinforced 70 concrete binding the ends of all of the vertical elements together.

This specification signed and witnessed this 2nd day of March, 1918.
